UNITED STATES PATENT OFFICE

GEORGE SABIK, OF WESTERN SPRINGS, ILLINOIS, ASSIGNOR TO U. S. DUPLICATOR COMPANY, OF CHICAGO, ILLINOIS, A CORPORATION OF ILLINOIS

DUPLICATING MACHINE

Application filed January 9, 1928. Serial No. 245,346.

This machine in its preferred form is of the type which employs a gelatine strip or band mounted on spools in such a way that a section thereof may be drawn across the top surface of the machine in position to receive a stencil impression which is thereafter reproduced on letter sheets or the like fed into the machine and compressed upon the gelatine surface containing the impression.

10 The object of the present invention is to construct a machine of this character so that the sheets may be easily and uniformly fed into the machine and thereafter registered in correct relation to the impression in the 15 gelatine and compressed thereon, and finally stripped therefrom and delivered in sequence at the far end of the machine without the necessity for manipulating the sheets by hand during the progress through the machine.

20 The invention also relates to the means provided for performing the above operations in continuous sequence by the constant travel of rollers and strippers in one and the 25 same direction, so that it will not be necessary, after taking an impression, to restore the mechanism to initial position which is quite common in machines of this character. By the means provided, the operations proceed 30 continuously, so that during the operations incident to the taking of one impression the next succeeding sheet may be fed into position in such a way as to be drawn into the machine during the delivery of the 35 preceding sheet, thereby speeding up the operation of the machine and enabling a multiplicity of impressions to be secured in the shortest period of time.

30 The invention relates in particular to the 40 arrangement of the feeding mechanism in such a way that the sheets will be caught and fed under a compression roller at the proper time, and also to the arrangement of the stripping rollers which engage the sheets and 45 automatically strip them from the gelatine surface without manual attention on the part of the operator.

50 The invention also relates to the means provided for transporting the imprinted sheets to the discharging position, to the

spool for carrying the gelatine strip, and to the means provided for permitting an end to end reversal thereof, as occasion may require, and to the construction and arrangement of the machine as a whole, all as will 55 more particularly and in detail appear from a description, in conjunction with the accompanying drawings, wherein—

Figure 1 is a side elevation of the machine;

Fig. 2 is a plan view thereof;

60 Figs. 3, 4, 5, 6, 7 and 8 are longitudinal sectional details taken at the infeeding end of the machine, showing in section the progress of a sheet of paper through the machine and illustrating the action of the impression and stripping rollers;

65 Fig. 9 is a longitudinal sectional detail showing the progress of the stripping operation;

70 Fig. 10 is a side elevation showing in more complete detail the mountings for the compression and stripping rollers;

75 Fig. 11 is a detail in plan showing the arrangement of the stripping rollers;

Fig. 12 is a cross sectional detail on line 75 12—12 of Fig. 10, showing the method of mounting and guiding the stripping rollers;

80 Fig. 13 is a detail showing one of the spools for the gelatine strip and the method of interchangeably mounting the same;

85 Fig. 14 is a detail showing the gear lock for preventing back rotation of the winding spool;

Fig. 15 is a detail of the latch for holding the journaled end of the spool in position in the frame;

85 Fig. 16 is a perspective showing the end of one of the spools and Figs. 17 and 18 show details of a modified form of roller mountings.

90 The machine as a whole is built upon a frame comprising elongated side plates 20 which are supported above a base frame comprising side rails 21 having medial standards 22 secured to the side plates, and end standards 23 and 24, the standards being duplicated on each side of the machine.

95 The standards 24 provide mountings for a shaft 25, which at each end affords a mounting for a sprocket wheel 26, the sprocket wheels being arranged exteriorly of the side 100

plates 20, and in like manner the standards 23 afford mountings for a shaft 27 carrying sprocket wheels 28 similarly positioned on opposite sides of the side plates 20.

5 The sprocket wheels 28 may be referred to for convenience as the front sprocket wheels, and the sprocket wheels 26 as the rear sprocket wheels; and the front and rear sprocket wheels on each side furnish the mountings for an endless chain carrier 29.

10 The front and rear pairs of sprocket wheels are keyed upon the respective shafts, so that power transmitted to the rear shaft on one side will impart rotation to both of the rear

15 sprocket wheels. For this purpose, a ring gear 30 is mounted upon the spokes of one of the sprocket wheels 26 and meshes with a pinion 31 which is driven through a sprocket train comprising a sprocket wheel 32, a 20 sprocket chain 33, and a sprocket wheel 34 on a driving shaft 35, which shaft is rotated by means of a handle 36, or by motor or other source of power. The details of the driving mechanism may be modified since they 25 form no essential part of the present invention.

30 The companion sprocket chains 29, which travel in unison on opposite sides of the machine, constitute carriers for the compression and stripping rollers, which will now be described in detail.

35 Each of the chains carries a pair of hook plates 37 and 38 provided with forwardly facing slots 39 and 40 respectively. The slots are arranged to receive a pair of pins 41 and 42, which stand outwardly from a frame plate 43 which occupies a position inside of the adjacent sprocket chain, as shown in Fig. 1. The arrangement is the same on each side of 40 the machine, so that a description of one of these plates and associated mechanisms will suffice for both.

45 The plates 43 are united by transversely extending tie rods 44 and 45 which in conjunction with the frame plates constitute a transversely extending carriage frame for the mounting of the compression roller 46 which serves to compress the paper sheet against the gelatine surface in the taking of 50 an impression.

55 The tie rods 44 and 45 are each surrounded by a sleeve 47, which sleeves serve to space the plates, the arrangement being one which affords the necessary rigidity to the carriage frame to prevent sagging or flexing as it is carried forward by the companion sprocket chains with which it is associated.

60 The compression roller 46 is mounted upon a shaft 48 carried at each end by a bracket arm 49, the bracket arms in each instance being pivoted upon a pin or stud 50, and each bracket arm is provided beyond the pivot with a finger 51 which is engaged by a spring 52 tending to swing the roller downwardly, a

stop pin 53 being provided to limit the action of the spring.

65 Each frame plate 43 is provided on its outer face with a face plate 54 which extends downwardly below the lower edge of 70 the face plate 43 and affords a mounting for a roller 55 which engages the lower face of a flange 56 (Fig. 12), which constitutes a trackway for the frame plate 43 which rests upon the upper face of the flange, the arrangement being one which permits the frame plates 43 of the carriage to ride freely along the flange on each side of the machine as the chain advances. 75

80 The gelatine strip or band 57 rests upon a table plate 58 which constitutes the upper surface of the machine, the edges of which table plate rest upon flanges 59 bolted or otherwise secured to the side walls 20. The gelatine strip or band at each end passes over an idle roller 60, and thence to a spool 61, which will presently be described more in detail.

85 Immediately in advance of the forward roller 60 is located a paper stop plate 62 which extends transversely of the machine, and is forwardly turned at its upper edge to afford an overhanging lip flange 63. The ends of the plate 62 are secured to rearwardly extending slotted arms 64, the slots of 90 which embrace a lug plate 65 on the proximate side wall 20, which arrangement permits the stop plate to be adjusted more or less to gauge the distance between the stop plate and the surface of the gelatine band. 100

95 The sheets of paper are carried upon a sloping feed plate 66 which, as shown in Fig. 2, is preferably provided with a plurality of ribs or corrugations 67. The sloping feed plate 66 is supported at its lower end between a pair of arms 68 which are mounted upon the projecting outer ends of the shaft 27, and the forward or upper end of the feed plate 66 is supported by a pair of brace rods 69 which extend downwardly to 110 and unite with the side rails 21, as shown in Fig. 1.

115 A stack of paper sheets A are laid upon the sloping surface of the feed plate, and one of the sheets is fed rearwardly and downwardly beneath a bridge bar 70 until it contacts with the paper stop 62 beneath the overhanging flanged edge or lip 63. An inspection of Figs. 3, 4, 5, 6 and 7 will show the progressive action of the compression roller 120 on the paper as the roller carriage advances from left to right.

125 As the carriage swings around the curved end of the frame plates 20, the spacer sleeve 47 of the tie rod 44 will first of all engage the under surface of the paper, as in Fig. 4, and lift it into contact with the overhanging lip 63. Thereafter, the compression roller 46 under spring tension will ride over the edge of the lip, as in Fig. 5, bearing against the 130

under surface of the paper and drawing it over the lip, as in Fig. 6, and impressing it against the gelatine surface.

By the time the roller has advanced to the 5 position indicated in Fig. 7, the paper will be laid flatwise upon the gelatine strip and the impression will be taken, so that thereafter the stripping of the paper will begin.

The stripping mechanism is mounted in a 10 manner quite similar to that heretofore described. The stripping mechanism is carried between side plates 71 which are held in spaced relation by tie rods 72, the plates 71 being provided with outstanding pins or 15 studs 73 and 74 which engage within the slots 75 and 76 respectively of hook plates 77 and 78 similar in all respects to those first described.

Each plate 71 is provided with a roller 79 20 which rides along the under surface of the guide flange 56 heretofore described, the roller being carried by an extension 80 which is secured to and depends below the plates 71.

The tie rods 72 are preferably surrounded 25 by spacer sleeves 81, which arrangement unites the side plate 71 into a rigid stripper carriage quite similar to the carriage first described.

The side plates of the stripper carriage 30 provide mountings for a pair of stripping rollers 82 and 83 mounted upon axle rods 84 and 85 respectively. The axle rod 85 at each end extends through a slot 86 in the adjacent plate 71, and receives a spring 87 which tends 35 to draw the roller 83 toward the roller 82, which latter is preferably provided with a rubber sheathing. The two rollers are in intermeshing relation with one another through the medium of gears 88 and 89, and the roller 40 82 is further provided with a driving pinion 90 which meshes with a rack 91 formed on or secured to the upper edge of the adjacent frame plate or wall 20, so that, as the carriage moves along the frame, both stripping rollers 45 will be positively driven and turn in opposition to one another.

The rack 91 at the rounded ends of the plates 20 is given an arcuate configuration as at 91^a, so that, as the stripper carriage 50 moves forwardly toward the point where it is to engage with the forward edge of the paper, the pinion 90 will engage with the rack and the rollers will thereafter begin to rotate and continue rotating during the stripping operation.

The manner in which the forward edge of the paper is gripped between the stripping rollers is best illustrated in Fig. 7, from which it will be seen that the forward edge of the 55 paper projects beyond the lip on the stop plate 63, so that, as the stripping rollers are carried forward, the rearmost roller will engage the forward edge of the paper and will feed it up into the bite of the rollers, as indicated in Fig. 8.

As the stripping operation progresses, the upturned end of the paper will encounter an obliquely extending shield 92 mounted upon the forward tie rod 72, which shield deflects the paper downwardly and causes it to rest 70 upon a series of cross bars 93 carried by standards 94 upstanding from the sprocket chains, which cross bars in unison constitute an elevated platform for the support of the paper sheet which is thus carried forward to the 75 rear end of the machine, at which point it discharges as the chain passes around the rear sprocket wheels.

In order to hold the two carriages in position, the ends of the pins or studs 42 and 74 80 respectively are each held in place by a pivoted latch 95, the hooked end of which is drawn upwardly by a spring 96, so that the pin 42, or 74 as the case may be, will be held against withdrawal, and with this latching arrangement on each side, each of the carriages is firmly held in position, but each may be easily removed, or replaced, as occasion 85 may require.

The winding spool 61 is duplicated at each 90 end of the machine, so that a description of one spool will apply to both. The gelatine strip or band is adapted to be fed from a spool mounted at or near the rear end of the machine, which may be termed the delivery 95 spool, to an identical spool at the forward end of the machine, which for the time being constitutes the winding spool, and in order that either spool may constitute the winding spool the spools are constructed as indicated 100 particularly in Figs. 13 and 16. As there shown, each spool at each end is provided with a cylindrical metal cap 97 having in its end a pair of sockets or apertures 98 on opposite sides of a centrally disposed spindle 99 which projects outwardly from a base 100.

Each of the spindles constitutes a journal mounting, and the pair of apertures at each 105 end constitute chuck sockets adapted to receive a pair of studs 101 on a boss 102 carried by a disk or plate 103 having gear teeth 104, as shown in Fig. 14.

The gear disk or plate 103 lies against the inner face of one of the side wall plates 20 and is provided in its center with an outstanding boss 105 provided with an outstanding squared head 106 adapted to receive the spindle of a winding handle 107, as indicated in dotted lines in Fig. 13.

The gear teeth 104 mesh with the teeth 110 120 of an idle pinion 109, and an intermediate locking pinion 110 meshes with both sets of teeth. The pinion 110 is free to ride upon the intermeshing gear teeth, so that as the gear disk 103 is rotated in a counter-clockwise direction, as in Fig. 4, the locking pinion 110 will be lifted, permitting the winding spindle to be rotated, but any effort to rotate the winding spindle in the reverse direction will cause the locking pinion to 125 130

drop back into the bite of the intermeshing teeth and prevent rotation thereof. The gear plate 111 overhangs the pinion and prevents displacement thereof.

5 The opposite side wall of the frame is illustrated in Fig. 15, and this wall is provided with an elongated slot 112, near the inner end of which is pivoted an L-shaped latch dog 113, the tail of which connects with a spring 114 which tends to lift the opposite end of the latch dog above the level of the slot 112, the arrangement being such that as the end spindle of the spool is swung toward the inner end of the slot the dog latch will be depressed and will snap upwardly as in Fig. 15 to hold the spindle journaled at the inner end of the slot.

10 In lieu of the roller mountings shown in Fig. 10, the simplified arrangement shown in Figs. 17 and 18 may be employed. In this case, in lieu of the plate 71, I employ a plate 115 which is directly secured to one of the links of the chain 21, the link pins 21^a in this instance being fixed in and projecting outwardly from the plate. The upper edge of the plate is provided with slots 116 and 117 the latter of which corresponds with the elongated slot 86 in the plate shown in Fig. 10. These slots receive the ends of the roller shafts 84 and 85 when the plate of Figs. 17 and 18 is used to support the stripping rollers and the shaft ends are held in place by a pivoted latch 18 which is notched on its under edge to complement the half bearings afforded by the slots.

15 The tie rods are secured to the plates in the manner already described and the rear end of the plate is hooked at 119 to receive the end of the first of the series of cross bars 93 for supporting the paper as it is stripped from the gelatine. A roller 120 engages the under side of the flange track 59 and a clip 121 is provided to bridge the upper side of the rack 91. In all material respects the plates 115 are similar to the plates 71 save that in the former case the companion plates on opposite sides of the machine in conjunction with the tie rods constitute a frame fixed to the chain from which the rollers are removable, while in the case of plates 71 the frame and rollers are together removable as a unit.

Operation

20 The operation of the machine may be briefly described as follows:

The gelatine strip rolled up on the delivering spool is mounted in position at the rear end of the machine to lie between the side walls of the frame, one wall of which is preferably provided with a slot and latch arrangement identical with that shown in Fig. 15, although any suitable method of journailling the spool may be provided.

25 The end of the gelatine strip is drawn forwardly over the surface of the table and se-

cured to the winding spool in any suitable manner, after which the winding spool may be tightened by turning the spindle by the use of a handle or other winding means. An impression is taken on the exposed portion of the gelatine band from a master copy, in the usual manner, after which the impressions may be taken. After a desired number of impressions have been taken, the gelatine strip may be advanced to expose a fresh section, and the process repeated from time to time until the entire length of the strip has been rolled up on the winding spool.

30 After allowing the exhausted strip to rest for a predetermined period, which permits the ink to recede from the surface of the gelatine, the strip may again be used, and in this instance the spool which previously acted as the winding spool will become the delivery spool, and the empty spool employed as the winding spool.

35 The gelatine strip, as it is again drawn across the table top, will be in reversed relation to that first occupied; that is to say, the side of the strip which previously lay on the right side of the machine will now lie on the left side of the machine, which is highly desirable, in that the ink impressions will be more uniformly distributed toward both sides of the strip than would be the case if the same side of the strip lay always in proximity to the same side of the machine. This method of reversal requires that either end of each spool may constitute the engaging end with the driving studs, and by forming the caps at each end of each spool with socket apertures either end of the spool may be engaged with the driving studs 101. The corresponding apertures at the opposite end of the spool will in no way interfere with the functioning of the associated spindle 99 which journals the spool at that end; and in like manner the spindle at the driving end will be received in a central aperture 115 while the studs 101 enter the apertures 98 in the proximate end of the spool, so that the driving will be effected at that end. This arrangement renders the spools interchangeable end for end at each end of the machine, which is highly desirable for the reasons stated.

40 With the gelatine strip or band properly adjusted the sheets of paper will be fed down from the feeding plate to rest against the stop plate, and as soon as the impression roller passes up over the forward end of the machine the lower end of the paper will be caught against the lip on the stop plate and the paper sheet will be swung over onto the gelatine surface as the spring-pressed compression roller rolls over the upper face of the lip 63, momentarily clamping the paper sheet during the interval of time it is being drawn out and thrown over into position on the gelatine surface; and imme-

5 diately thereafter the compression roll will begin to press down against the gelatine so that the end of the paper will be constantly gripped and compressed with no opportunity for its displacement during the interval of time it is being swung over into position on the gelatine surface.

As the chain advances, the compression roller will smooth out the paper and forcibly 10 compress the same against the gelatine to receive the impression. The stripper carriage with the stripping rollers follows after the compression carriage with its roller and engages the forward edge of the paper, 15 which in every instance will project slightly beyond the lip 63, as in Fig. 7, so that the stripping rollers will have an opportunity to grip the unsupported forward edge of the paper and carry the same up into the bite 20 of the rollers, which is necessary in order to properly strip the paper from the gelatine surface.

As shown in Fig. 9, the stripping rollers stand in elevated relation above the gelatine surface, so that the paper will be lifted 25 up between the rollers and smoothly and evenly strip away from the gelatine and feed over to the supporting rods 93, which constitute, in effect, a platform for conveying 30 the paper sheet to the far end of the machine where it will be automatically discharged as the rods swing downwardly as the sprocket chains pass over the rear sprocket wheels.

As shown in Fig. 1, the machine is provided with two sets of mechanisms, so that 35 as the first sheet is being stripped a second sheet may be positioned against the stop plate in preparation for the arrival of the compression roller of the second group of 40 mechanisms, and obviously the machine might be elongated to provide for the mounting of three or more sets of compressing and stripping mechanisms as occasion might require. The movement of the chain being 45 continuous, there will be no loss of time occasioned by a restoring movement of the mechanisms, so that the machine may be continuously operated at an expenditure of a minimum of power, either by hand or by a 50 motor, as the case may be.

The invention is one which combines simplicity in construction with speed and precision in operation. Although the apparatus has been described with considerable particularity as to detail, it is not the intention 55 to limit the invention to the specific construction shown, since variations in detail might be provided for without departing from the spirit of the invention.

60 I claim:

1. In a duplicating machine, the combination of a frame adapted to hold a duplicating surface, a paper stop near one end of the position to be occupied by said duplicating 65 surface in position to arrest a sheet of paper

fed toward said surface, and a movable impression roller mounted to be moved from a position beneath the stopped end of said paper to contact said paper and swing the same over said stop and onto said duplicating 70 surface, substantially as described.

2. In a duplicating machine, the combination of a frame adapted to hold a duplicating surface, a paper stop near one end of the position to be occupied by said duplicating 75 surface in position to arrest a sheet of paper fed toward said surface, and a movable impression roller mounted to be moved from a position beneath the stopped end of said paper to contact said paper and swing the same over 80 said stop and onto said duplicating surface, said roller being spring pressed and adapted, in conjunction with the said stop, to clamp the end of the paper as the roller rides over said stop, substantially as 85 described.

3. In a duplicating machine, the combination of a frame adapted to hold a duplicating surface, a paper stop near one end of the position to be occupied by said duplicating 90 surface in position to arrest a sheet of paper fed toward said surface, a movable impression roller mounted to be moved from a position beneath the stopped end of said paper to contact said paper and swing the same over 95 said stop and onto said duplicating surface, said roller being spring pressed and adapted, in conjunction with the said stop, to clamp the end of the paper as the roller rides over said stop, and a cross rod associated and movable 100 with said impression roller to initially lift the end of said paper into engaging relation with said stop, substantially as described.

4. In a duplicating machine, the combination of a frame adapted to hold a duplicating surface, a paper stop near one end of the position to be occupied by said duplicating surface in position to arrest a sheet of paper fed toward said surface, a movable impression roller mounted to be moved from a position beneath the stopped end of said paper to contact said paper and swing the same over 105 said stop and onto said duplicating surface, and a stripper movable with and behind said impression roller and adapted to engage the 110 forward end of said paper and strip the same from the impression surface, substantially as described.

5. In a duplicating machine, the combination of a frame adapted to hold a duplicating surface, a paper stop near one end of the position to be occupied by said duplicating 120 surface in position to arrest a sheet of paper fed toward said surface, a movable impression roller mounted to be moved from a position beneath the stopped end of said paper to contact said paper and swing the same over said stop and onto said duplicating surface, said roller being spring pressed and adapted, in conjunction with the said stop, to clamp 125

the end of the paper as the roller rides over said stop, and a stripper movable with and behind said impression roller and adapted to engage the forward end of said paper and strip the same from the impression surface, substantially as described.

5 6. In a duplicating machine, the combination of a frame adapted to hold a duplicating surface, a paper stop near one end of the position to be occupied by said duplicating surface in position to arrest a sheet of paper fed toward said surface, a movable impression roller mounted to be moved from a position beneath the stopped end of said paper to contact said paper and swing the same over said stop and onto said duplicating surface, said roller being spring pressed and adapted, in conjunction with the said stop, to clamp the end of the paper as the roller rides over said stop, a cross rod associated and movable with said impression roller to initially lift the end of said paper into engaging relation with said stop, and a stripper movable with and behind said impression roller and adapted to engage the forward end of said paper and strip the same from the impression surface, substantially as described.

10 7. In a duplicating machine, the combination of a frame, adapted to hold an impression surface, an impression carriage movable along said frame, a spring pressed impression roller carried by said carriage, a stop at the forward end of the position to be occupied by said impression surface, said stop being provided with an angularly disposed flange constituting a lip, a supporting plate for sheets of paper positioned to permit each sheet to be fed to a position to contact said stop beneath the lip, the relation of the parts being such that as the impression roller is moved it will initially clamp the paper against the lip and thereafter swing the paper over the stop and onto the impression surface and compress the paper upon said surface, substantially as described.

15 8. In a duplicating machine, the combination of a frame, adapted to hold an impression surface, an impression carriage movable along said frame, a spring pressed impression roller carried by said carriage, a stop at the forward end of the position to be occupied by said impression surface, said stop being provided with an angularly disposed flange constituting a lip, a supporting plate for sheets of paper positioned to permit each sheet to be fed to a position to contact said stop beneath the lip, the relation of the parts being such that as the impression roller is moved it will initially clamp the paper against the lip and thereafter swing the paper over the stop and onto the impression surface and compress the paper upon said surface, and stripping rollers movable uniformly with and behind the impression roller

and positioned to engage the end of the paper projecting beyond said stop and strip the paper from the impression surface, substantially as described.

19 9. In a duplicating machine, the combination of a frame, adapted to hold an impression surface, an impression carriage movable along said frame, a spring pressed impression roller carried by said carriage, a stop at the forward end of the position to be occupied by said impression surface, said stop being provided with an angularly disposed flange constituting a lip, a supporting plate for sheets of paper positioned to permit each sheet to be fed to a position to contact said stop beneath the lip, the relation of the parts being such that as the impression roller is moved it will initially clamp the paper against the lip and thereafter swing the paper over the stop and onto the impression surface and compress the paper upon said surface, stripping rollers movable uniformly with and behind the impression roller and positioned to engage the end of the paper projecting beyond said stop and strip the paper from the impression surface, and an elevated support movable behind the stripping rollers and adapted to receive and transport the paper sheets to discharging position, substantially as described.

75 10. In a duplicating machine, the combination of a frame adapted to hold an impression surface, a pair of endless carriers mounted to bring their upper turns into parallel relation with the impression surface on each side thereof, an impression carriage having its ends secured to said endless carriers, a spring pressed impression roller carried by said carriage and adapted to bear downwardly upon said impression surface, a paper stop located in proximate relation to the position to be occupied by the impression surface and adapted to arrest the sheets of paper when fed to position, the relation of the stop and impression roller being such that the latter will initially clamp the paper against the stop and thereafter move the paper to contacting relation with the impression surface, substantially as described.

80 11. In a duplicating machine, the combination of a frame adapted to hold an impression surface, a pair of endless carriers mounted to bring their upper turns into parallel relation with the impression surface on each side thereof, an impression carriage having its ends secured to said endless carriers, a spring pressed impression roller carried by said carriage and adapted to bear downwardly upon said impression surface, a paper stop located in proximate relation to the position to be occupied by the impression surface and adapted to arrest the sheets of paper when fed to position, the relation of the stop and impression roller being such that the latter will initially clamp the paper against the stop

and thereafter move the paper to contacting relation with the impression surface, a stripper carriage having its ends secured to the endless carriers and positioned to follow the impression carriage, and stripping elements carried by the stripper carriage and adapted to strip the paper from the impression surface, substantially as described.

12. In a duplicating machine, the combination of a frame adapted to hold an impression surface, a pair of endless carriers mounted to bring their upper turns into parallel relation with the impression surface on each side thereof, an impression carriage having its ends secured to said endless carriers, a spring pressed impression roller carried by said carriage and adapted to bear downwardly upon said impression surface, a paper stop located in proximate relation to the position to be occupied by the impression surface and adapted to arrest the sheets of paper when fed to position, the relation of the stop and impression roller being such that the latter will initially clamp the paper against the stop and thereafter move the paper to contacting relation with the impression surface, a stripper carriage having its ends secured to the endless carriers and positioned to follow the impression carriage, and stripping elements carried by the stripper carriage and adapted when moved to a position adjacent to the stop to engage the end of the paper sheet between the rollers and strip the same from the impression surface, substantially as described.

13. In a duplicating machine, the combination of a frame adapted to hold an impression surface, a pair of endless carriers mounted to bring their upper turns into parallel relation with the impression surface on each side thereof, an impression carriage having its ends secured to said endless carriers, a spring pressed impression roller carried by said carriage and adapted to bear downwardly upon said impression surface, a paper stop located in proximate relation to the position to be occupied by the impression surface and adapted to arrest the sheets of paper when fed to position, the relation of the stop and impression roller being such that the latter will initially clamp the paper against the stop and thereafter move the paper to contacting relation with the impression surface, a stripper carriage having its ends secured to the endless carriers and positioned to follow the impression carriage, stripping elements carried by the stripper carriage and adapted when moved to a position adjacent to the stop to engage the end of the paper sheet between the rollers and strip the same from the impression surface, substantially as described.

14. In a duplicating machine, the combi-

nation of a frame adapted to hold an impression surface, a pair of endless carriers mounted to bring their upper turns into parallel relation with the impression surface on each side thereof, an impression carriage having its ends secured to said endless carriers, a spring pressed impression roller carried by said carriage and adapted to bear downwardly upon said impression surface, a paper stop located in proximate relation to the position to be occupied by the impression surface and adapted to arrest the sheets of paper when fed to position, the relation of the stop and impression roller being such that the latter will initially clamp the paper against the stop and thereafter move the paper to contacting relation with the impression surface, a stripper carriage having its ends secured to the endless carriers and positioned to follow the impression carriage, stripping elements carried by the stripper carriage and adapted when moved to a position adjacent to the stop to engage the end of the paper sheet between the rollers and strip the same from the impression surface, a rack on the frame, gear elements in train with said rack for positively driving one of the stripping rollers, and an elevated support having its ends secured to the endless carriers and positioned behind the stripper carriage in position to receive the sheets stripped from the impression surface and carry them to discharging position, substantially as described.

15. In a duplicating machine, the combination of a frame adapted to hold an impression surface, a pair of endless carriers located one on each side of the frame and mounted to travel in parallel relation to the impression surface, an impression carriage having its ends secured to the endless carriers and having a guide roller secured to each end, a track flange on each side of the frame in position to be engaged from beneath by the proximate guide roller, a spring pressed impression roller carried between the ends of the carriage and positioned to be held under spring tension in contact with the impression surface, and a paper stop adapted to arrest a sheet of paper in proximate relation to the impression surface and in position to be engaged by the impression roller, substantially as described.

16. In a duplicating machine, the combination of a frame adapted to hold an impression surface and provided with a longitudinally extending rack at one side thereof, a pair of endless carriers located one on each side of the frame and mounted to travel in parallel relation to the impression surface, an impression carriage having its ends secured to the endless carriers and having a guide roller secured to each end, a track flange on each side of the frame in position to be engaged from beneath by the proximate

guide roller, a spring pressed impression roller carried between the ends of the carriage and positioned to be held under spring tension in contact with the impression surface, a paper stop adapted to arrest a sheet of paper in proximate relation to the impression surface and in position to be engaged by the impression roller, a stripper carriage having its ends secured to the endless carriers and having on each end a guide roller positioned to contact the under surface of the guide flange, and spring roller elements carried by the stripper carriage and having a gear train in mesh with said rack, one of said roller elements being adapted to move beneath the surface of the paper sheet to strip the same from the impression surface, substantially as described.

17. In a duplicating machine, the combination of a frame adapted to hold an impression surface and provided with a longitudinally extending rack at one side thereof, a pair of endless carriers located one on each side of the frame and mounted to travel in parallel relation to the impression surface, an impression carriage having its ends secured to the endless carriers and having a guide roller secured to each end, a track flange on each side of the frame in position to be engaged from beneath by the proximate guide roller, a spring pressed impression roller carried between the ends of the carriage and positioned to be held under spring tension in contact with the impression surface, a paper stop adapted to arrest a sheet of paper in proximate relation to the impression surface and in position to be engaged by the impression roller, a stripper carriage having its ends secured to the endless carriers and having on each end a guide roller positioned to contact the under surface of the guide flange, spring roller elements carried by the stripper carriage and having a gear train in mesh with said rack, one of said roller elements being adapted to move beneath the surface of the paper sheet to strip the same from the impression surface, and a plurality of cross bars having their ends secured to the endless carriers and adapted to travel above the level of the impression surface and receive and support paper sheets stripped therefrom and convey them to discharging position; substantially as described.

18. In a duplicating machine, the combination of a frame provided with side walls, each wall having on its upper edge a longitudinally extending rack and a guide rail below the rack, a pair of front sprocket wheels located one on each side of the frame, a pair of rear sprocket wheels located on each side of the frame, endless chains on each side of the frame mounted upon the corresponding sprocket wheels, means for rotating the sprocket wheels to impart uniform rotation to both of the chains, an impression carriage

having end plates secured to the respective chains, an impression roller carried between the end plates, a spring for holding said roller in compressive relation, the frame being adapted to mount an impression surface 70 adapted to be contacted by said roller, guide rollers on the end plates of the carriage positioned to contact the under surface of the track flange, a stripper carriage provided with end plates secured respectively to the 75 endless chains, guide rollers on the end plates to engage with the under surfaces of the respective track flanges, stripping rollers carried between the end plates of the stripper carriage, and gear elements on the rollers in train with the racks, substantially as described.

19. In a duplicating machine, the combination of a frame provided with side walls, each wall having on its upper edge a longitudinally extending rack and a guide rail below the rack, a pair of front sprocket wheels located one on each side of the frame, a pair of rear sprocket wheels located on each side of the frame, endless chains on each side of the frame mounted upon the corresponding sprocket wheels, means for rotating the sprocket wheels to impart uniform rotation to both of the chains, an impression carriage having end plates secured to the respective 85 chains, an impression roller carried between the end plates, a spring for holding said roller in compressive relation, the frame being adapted to mount an impression surface 90 adapted to be contacted by said roller, guide rollers on the end plates of the carriage positioned to contact the under surface of the track flange, a stripper carriage provided with end plates secured respectively to the 95 endless chains, guide rollers on the end plates to engage with the under surfaces of the respective track flanges, stripping rollers carried between the end plates of the stripper carriage, gear elements on the rollers in train with the racks, and a paper stop in proximate 100 relation to the impression surface and provided at its upper edge with an overhanging lip, the stop being positioned to be contacted by the impression roller to clamp the end of the paper sheet against the lip as the roller passes over the lip and onto the impression surface for swinging the paper sheet onto said surface and compressing the same thereon, substantially as described.

GEORGE SABIK. 120
